UNITED STATES PATENT OFFICE.

SAMUEL CRAIG AND JOHN CRAIG, OF GARDEN CITY, KANSAS.

DESIGN FOR A WEED-HOE.

SPECIFICATION forming part of Design No. 26,183, dated October 13, 1896.

Application filed September 1, 1896. Serial No. 604,588. Term of patent 14 years.

To all whom it may concern:

Be it known that we, SAMUEL CRAIG and JOHN CRAIG, citizens of the United States, residing at Garden City, in the county of Finney 5 and State of Kansas, have invented a new and original Design for Weed-Hoes, of which the following is a specification.

This invention relates to a new and original design for weed-hoes; and it has for its object to provide a design of this character that shall be both useful and ornamental.

The leading feature of the design resides in a hoe having an elongated handle, a blade comprising oppositely-extending portions disposed at an angle to each other and forming a V-shaped figure with a symmetrically-rounded apex, said blade being of a triangular shaped cross-section, and a series of branched arms merging together at one end of the handle and respectively connecting with the blade at its opposite ends and at its central apex, the central arm being alined with the handle and the side arms being compoundly curved outward from their connection with said central arm.

In the drawings, Figure 1 is a perspective view of a hoe embodying the herein-described design. Fig. 2 is a front elevation thereof. Fig. 3 is a cross-sectional view of the blade. Referring particularly to the drawings, the

numeral 1 designates a weed-hoe having an elongated cylindrical handle 2 and a blade 3. The blade 3 comprises separate oppositely-extending portions 4, disposed at an angle to each other and forming a V-shaped figure 35 with a symmetrically-rounded apex 5 at its outer edge. The blade is triangular in cross-section and is joined with the handle by a series of branched arms 6. The branched arms 6 merge together at one end of the handle, as at 7, and respectively connect with the blade at its opposite ends and at its central apex, the central arm being alined with the handle and having an elliptically-shaped foot-piece 8 on the upper face of the blade, 45 and the side arms 6 being compoundly curved outwardly, as at 8^a, from their connections with said central arms.

What we claim is—

The design for a weed-hoe herein shown and 50 described.

In testimony that we claim the foregoing as our own we have hereto affixed our signatures in the presence of two witnesses.

SAMUEL CRAIG.
JOHN CRAIG.
